UNITED STATES PATENT OFFICE.

JAMES H. RAND, OF NEWTONVILLE, MASSACHUSETTS.

ACCOUNT-BOOK.

SPECIFICATION forming part of Letters Patent No. 744,793, dated November 24, 1903.

Application filed September 17, 1903. Serial No. 173,585. (No model.)

To all whom it may concern:

Be it known that I, JAMES H. RAND, a citizen of the United States, residing at Newtonville, in the county of Middlesex and State of Massachusetts, have invented new and useful Improvements in Account-Books, of which the following is a specification.

This invention relates to the daily-balance ledgers used in banks, and more particularly to ledgers of this class in which each section is provided with a movable index or supplemental list of depositors' names capable of being placed beside those entry-columns which are more or less remote from the usual name-column at the left-hand margin of the leaves, so as to bring the names closely to such remote columns and enable the bookkeeper to work more rapidly and with comparatively little risk or making an entry on the wrong line.

The object of my invention is to provide such ledgers with a movable index of this kind which is simple in construction, easily manipulated, and reliably held in its proper position.

In the accompanying drawings, consisting of two sheets, Figure 1 is a perspective view of an open bank-ledger embodying my invention. Fig. 2 is a detached face view, partly in section, of one of the sections of the ledger, showing a different position of the reversible index. Fig. 3 is a transverse section in line 3-3, Fig. 2, on an enlarged scale. Fig. 4 is a fragmentary sectional view, on an enlarged scale, of the swinging index-frame and the binding-stub to which it is attached, showing the construction of the hinge. Fig. 5 is a perspective view of one of the pintles to which the swinging frame is attached, showing the manner of securing its flexible connection to the pintle.

Similar letters of reference indicate corresponding parts throughout the several views.

A indicates the leaves of the book, and B the usual column of depositors' names, written or printed upon the left-hand margin of the leaves, the names being arranged in alphabetical order in a manner common to such ledgers.

The leaves are ruled into groups of vertical columns C for the entry of debits and credits or deposits, checks, and balances, each

group being headed by the name of one of days of the week and the several columns being subdivided into horizontal entry-spaces 55 d, which register with the spaces of the name-column B in a well-known manner. In the ledger shown in the drawings each page has six groups of columns; but, if desired, each may have three groups. The leaves may be 60 permanently or loosely bound in the book. In the ledger illustrated in the drawings they are arranged in sections, each of which is attached to a stub e, which is removably bound in the book like the leaves of loose-leaf 65 ledgers; but this particular feature forms no part of my present invention and is the subject of another application filed by me February 24, 1903, Serial No. 144,877.

Combined with each section of the book is 70 a movable index F, which extends across the leaves of the section parallel with the vertical account-columns and which bears on both sides a duplicate of the depositors' names printed on the leaves of the corresponding 75 section. Each of these movable indexes consists of a narrow strip of stiff material, such as cardboard or sheet metal, which is pivotally attached at one of its longitudinal edges to the free end of a swinging frame G, hinged 80 to the center or back of the book, so that the index can be turned or reversed on the frame, and the latter can be thrown to either side of the open book. This frame is approximately 85 U-shaped and composed of longitudinal or side bars g, extending along the upper and lower edges of the leaves, and a transverse bar g', connecting the outer ends of said bars, the three bars being formed in one piece and preferably made flat-sided. The index F is 90 provided at its inner edge with a flexible flat-sided pocket or loop f, of fabric or similar strong material, which receives the flat-sided transverse bar g' of the swinging frame. This bar is fitted snugly in the pocket of the index, so that in turning the index from one 95 side of the bar to the other the sides of the pocket are bulged or spread until the index reaches a position parallel with the page, when the pocket again contracts to its flat-sided form. By this construction the pocket offers sufficient resistance to the turning of the index to prevent accidental rotation or 100 displacement of the same.

The swinging frame, which carries the index, may be hinged to the center of the book by any suitable means; but I prefer to employ for this purpose rods or pintles *h*, seated in pockets or loops *i*, arranged at the outer edges of the binding-stubs *e*, and closely-coiled spiral springs *k*, which connect the outer ends of said pintles with the inner ends of the side bars *g* of the swinging frame. 5 These springs form flexible connections, which permit the transverse bar *g'* of said frame and the index *F* to lie flat upon the leaves of the book. The springs are preferably provided at their inner ends with angular extensions *k'*, which are fitted in longitudinal openings formed in heads or lateral enlargements *l* at the outer ends of the pintles, the extensions being confined in these openings by bending over or upsetting their ends, 10 as shown at *k*² in Figs. 4 and 5.

The side bars *g* of the swinging frame are preferably of such a length that in a ledger having its pages ruled into six divisions to receive a full week's entries the transverse bar 15 *g'* lies between the Thursday and Friday columns or divisions of the left-hand pages and between the Tuesday and Wednesday columns of the right-hand pages of the book. If each page is ruled to receive entries for 20 three days only, the swinging frame is made of the proper size to locate its outer bar *g'* between the Tuesday and Wednesday columns of the left-hand pages and between the Thursday and Friday columns of the right-hand 25 pages.

In the use of the movable index with a ledger of the kind illustrated in the drawings when entering Monday's, Tuesday's, and Wednesday's work the index is turned to the 30 left-hand side of the bar *g'*. In entering Thursday's work the index is turned to the right of said bar, as shown in Fig. 1, so as to expose the Thursday column. In entering Friday's and Saturday's work the index is 35 turned to the left of the bar *g'*, as shown in Fig. 2. After filling the left-hand page the swinging frame is thrown upon the opposite or right-hand page and the index is turned to the right or left, as before described. In this 40 manner the list of depositors' names is always brought close to the column in which entries are being made, enabling the bookkeeper to work quickly and with the least liability of making entries on the wrong line.

50 My improvement is herein shown in connection with a daily-balance ledger; but the 55

same is equally applicable to other record and account books.

I claim as my invention—

1. An account or record book having a 60 hinged frame capable of swinging to either side of the open book and an index attached at one edge to the free end of said frame, substantially as set forth.

2. An account or record book having a 65 hinged frame capable of swinging to either side of the open book, and a reversible index pivoted at one edge to the free end of said frame, substantially as set forth.

3. An account-book having its pages ruled 70 into columns or divisions provided with headings denoting different days of the week, a hinged frame capable of swinging to either side of the open book and having its transverse outer bar arranged to lie between two 75 adjacent columns or divisions of the pages, and a reversible index pivoted at one edge to said transverse bar, substantially as set forth.

4. An account or record book provided with a hinged frame capable of swinging to either 80 side of the open book and having a flat-sided bar at its free end, and a reversible index provided at one edge with a flexible pocket which receives said bar, substantially as set forth.

5. An account or record book provided at 85 its back or center with pintles, a swinging frame comprising side bars arranged along the upper and lower edges of the leaves and a transverse bar connecting the outer ends of 90 said side bars, spiral springs connecting said side bars with said pintles, and an index carried by said frame, substantially as set forth.

6. An account or record book provided at 95 its back or center with a pocket, pintles seated in said pocket and provided at their outer ends with perforated enlargements, a swinging frame comprising side bars and a transverse bar connecting the outer ends of said 100 side bars, spiral springs secured at their outer ends to said side bars and provided at their inner ends with angular extensions which are secured in the perforated enlargements of the pintles, and an index carried by said frame, substantially as set forth.

105 Witness my hand this 14th day of September, 1903.

JAMES H. RAND.
